(57) **CLAIM**

The ornamental design for a tree lamp, as shown and described.

DESCRIPTION

FIG. 1 is a front, right, and top perspective view of a first embodiment of a tree lamp, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1 comprising a branch.

FIG. 10 is a partial enlarged view of an area labeled 10 in FIG. 1 comprising a branch.

FIG. 11 is a front, right, and top perspective view of a second embodiment of a tree lamp.

FIG. 12 is a front, right, and top perspective view of a third embodiment of a tree lamp.

FIG. 13 is a front, right, and top perspective view of a fourth embodiment of a tree lamp.

FIG. 14 is a front, right, and top perspective view of a fifth embodiment of a tree lamp; and,

FIG. 15 is a front, right, and top perspective view of a sixth embodiment of a tree lamp.

The broken lines shown in the drawings are included for the purpose of illustrating portions of the tree lamp that form no part of the claimed design.

1 Claim, 15 Drawing Sheets
